WILLIAM L. WALKER, OF NEW YORK, N. Y., ASSIGNOR TO WALKER SIGNAL & EQUIPMENT CORPORATION, A CORPORATION OF DELAWARE

MULTIPLE-CONTROL SWITCH

Application filed May 31, 1929. Serial No. 367,345.

This invention relates to improvements in switches and is concerned more particularly with multiple control switches such as is disclosed in my application Serial No. 165,606 filed February 3, 1927 now Patent No. 1,773,830 issued August 26, 1930 and which are designed to control a plurality of electric circuits by the movement of a single switch handle into various positions. The present invention comprises an improvement over the type of switch disclosed in the application referred to above and is particularly adapted to be used in connection with sonic direction finders, fire control and various intercommunicating systems used on board ships.

Owing to the use of switches of the present type on board ships where they are often surrounded by moist salty air and subjected to heavy shocks and other unusual conditions the switches must be of efficient and reliable design so that they can be depended upon to function at the proper time with a minimum of attention and effort on the part of the operator.

The principal object of the present invention, therefore, is to provide a multiple control switch of rugged design so that it will stand up well in service, and at the same time to provide a switch in which the number of machine parts shall be small and simple in shape and cost of labor required to assemble the switch will be quite low so that the ultimate price of the switch may also be low.

Another object is to provide a switch of such construction that all of its parts will be easily replaceable and which may be easily assembled and dismantled with a minimum of labor.

As a switch of the present type may comprise a large number of poles, eighteen or more being not an unusual number, it would ordinarily require considerable power to rotate the switch into its various positions unless means are provided to reduce the friction between the brush contacts and the conducting discs or plates of the switch. In order to reduce this friction to a minimum the switch is so designed that the brushes when not contacting with the conducting

plates contact with insulating washers, the total thickness of which is substantially less than the width of the conducting plates. In the present design it is possible to so proportion the insulating washers that the friction on the brushes may be reduced as much as 60 or 70% thereby reducing the effort necessary to rotate the switch correspondingly.

In multiple control switches in which a large number of circuits are to be made and broken it is necessary that a large number of conducting plates and their associated brushes be employed. The conducting plates must be properly insulated from one another and usually washers of hard rubber or other non-conducting material are employed for this purpose. However, it is not possible to obtain washers of absolutely uniform thickness and it therefore becomes necessary to provide means for adjusting the brushes independently with respect to the conducting discs or plates.

Another object of the present invention, therefore, is to provide means in multiple control switches whereby brushes may be independently located so that they may be properly positioned with respect to the conducting discs or plates and at the same time will provide a quick action upon breaking the contacts of the brushes with the discs.

Another object of the present invention is to provide means whereby the wear on the brush contacts may be taken up so that the brushes will have a substantially constant pressure on the conducting discs or plates as they wear away. This may be done by providing brushes of resilient material which normally urge the brush contacts toward the conducting discs or plates. However, the present invention describes means in addition to the resilient brushes, these means comprising a mounting of the brushes upon supporting rods which are rotatably mounted and normally urged in a direction to force the brushes toward the conducting discs. By means of these features of the present invention the brush contacts are not only independently urged toward the conducting discs or plates, but all of the brushes mounted upon a given supporting rod are collectively urged

toward the conducting discs or plates. By virtue of this construction if a single brush be caused to wear away faster than the remaining brushes its pressure on the conducting discs or plates will remain constant by reason of the independent resiliency of its brush.

A further object of the present invention is to provide conducting discs or plates of such design that the spark which occurs when the circuit is broken will be confined in a chamber formed between the insulating discs on either side of the conducting discs or plates. The shape of certain of the conducting plates is such that the spark does not occur on the surface which contacts with the brushes so that this surface is not pitted by the sparking and consequently the friction between the conducting plates and the brushes is not increased thereby.

A still further object of the present invention is to provide reversible metal brush contacts which may be reversed when one side thereof is worn through contact with the conducting discs or plates, thus greatly lengthening the life of the brush contacts.

Another object of the invention is to provide coiled spring brushes which give greater flexibility with equal conductivity.

Further objects of the invention will be apparent from the description herein set forth.

In general, the switches embodying the present invention comprise two spaced circular end plates adapted to support a central shaft, one end of which projects a substantial distance beyond one of the end plates and has connected to its end a handle for rotating the switch. Upon the central shaft are mounted a plurality of conducting plates with suitable washers of insulating material, such as hard rubber therebetween. These conducting plates comprise two different types (1) circular discs with which one series of brushes is always in contact, and (2) substantially rectangular plates provided with a segmental projection extending beyond the insulating discs and adapted to contact with other series of brushes. The two sets of plates are mounted alternately on the central shaft and each set of two adjacent plates is electrically connected by suitable means, such as, for example, a screw. The plurality of rods upon which the various series of brushes are mounted are distributed equally about the central shaft and are rotatably supported in the two spaced end members. Coiled springs associated with the brush supporting rods normally urge these rods in such a direction as to force the brushes mounted thereon toward the conducting plates. Suitable stops are provided on the ends of the brush rods to limit the rotative movement of the rods. A disc having a series of equally spaced notches cut therein,

corresponding in number to the number of throws of the switch is mounted on one end of the central shaft. A member pivotally connected with one of the end plates is provided with a roller adapted to roll along the surface of this disc and be inserted into the notches when the central shaft is rotated into its various circuit connecting positions.

In order to understand the invention fully reference may be had to the following description and the accompanying drawings in which:

Fig. 1 is a partial longitudinal cross sectional view taken substantially along the line 1—1 of Fig. 2 and illustrates a preferred embodiment of the present invention.

Fig. 2 is a cross sectional view taken substantially along the line 2—2 of Fig. 1.

Fig. 3 is a cross sectional view taken substantially along the line 3—3 of Fig. 1.

Fig. 4 is an end view of the switch with a portion of the end supporting plate being broken away to show a coiled spring mounted on one of the brush supporting rods.

Fig. 5 is a partial cross sectional view through the central shaft showing the arrangement of the two sets of conducting plates mounted thereon with the insulating discs or washers therebetween.

Fig. 6 is a partial cross sectional view illustrating a modified form of brush supporting means.

Fig. 7 is a longitudinal view thereof.

Fig. 8 is a partial cross sectional view illustrating another modification of brush supporting means.

Fig. 9 is a longitudinal view thereof, and

Fig. 10 is a sectional view of the quick action contact breaker.

In the drawing which illustrates a preferred embodiment of the present invention the numerals 1 and 2 indicate two spaced end plates preferably circular and adapted to support the switch mechanism. The end plates 1 and 2 are held in fixed relation by a convenient number of tie rods 3, four such rods being illustrated. A central shaft 4 is rotatably mounted in the center of the end plates 1 and 2 and one end of the shaft projects a substantial distance beyond the plate 2 and has connected thereto a handle 5 adapted to rotate the central shaft.

The central shaft 4 has mounted thereon a plurality of conducting plates whose number depends upon the number of circuits to be made and broken by the switch. The type of the switch illustrated in the drawing may comprise a large number of poles, for example, 18, and has six throws, including an "off" position. The conducting plates mounted on the central shaft 4 comprise two different types (1), circular discs 6 and (2), substantially rectangular plates 7. The two sets of plates are insulated from the central shaft by means of a tube 8 of non-conducting ma-

terial inserted between the shaft and the plates and the plates are insulated from one another by the discs or washers 9 of suitable insulating material, such as hard rubber. As shown more clearly in Fig. 5 the two types of plates 6 and 7, respectively, are mounted alternately upon the central shaft 4. In an 18 hole switch there will be 18 such pairs of conducting plates 6 and 7. In order to prevent the conducting plates 6 and 7 from moving with respect to one another on the central shaft 4, a rod 10 having suitable insulation 11 thereon is passed through the plates as indicated in Fig. 1. The conducting discs 6 which are circular in form are of slightly less diameter than the insulating washers 9. These discs are made circular because the brushes connected with one set of terminals of the switch are in continuous contact with these conducting discs. The other of the conducting plates 7 are substantially rectangular as shown in Fig. 2 and are provided with arcuate segments as indicated at 12, which segments are of slightly greater radii than the radii of the insulating washers 9 so that they project above these washers. The ends of the conducting plates 7 adjacent these projecting segments 12 are bevelled off as indicated at 13 at some convenient angle such as, for example, 45° so that the only portions of the conducting discs 7 extending beyond the periphery of the insulating washers 9 are the projecting segments 12. In order to provide a circuit between each pair of conducting plates 6 and 7, these plates are connected by means of the screws 14 as clearly illustrated in Fig. 5. Insulating washers 15 are preferably inserted on the central shaft 4 between the conducting discs 6 and the insulating washers 9 as shown in Fig. 5.

The brushes which contact with the conducting plates 6 and 7 are mounted upon brush rods 16 which extend substantially the full distance between the end plates 1 and 2 and are rotatably supported thereby, and which are distributed equally distant about the central shaft 4. In a switch having five "on" positions and one "off" position there are six brushes necessary for each pair of conducting plates 6 and 7 so that there will be six pairs of brush supporting rods 16. In the embodiment of the invention shown in Fig. 1, double brush supporting rods are employed and have connected to their ends journal members 17 which comprise a rectangular portion 18 having spaced holes therein adapted to receive the ends of the brush supporting rods 16. The journals 17 are provided with projections 19 which extend a slight distance beyond the face of the end plates 1 and 2. The journals 17 are rotatably supported in bushings 20 threaded into the end plates 1 and 2 as indicated at 21.

In order to take up the wear on the brush

contacts due to their rubbing on the conducting plates 6 and 7 means are preferably provided to rotate the brush supporting rods in a direction tending to force the brushes toward the conducting plates. Various means may be employed for thus rotating the brush rods, but the means preferably employed in the present invention comprise coiled springs 22 wound about the journal members 17 between the projections 18 thereon and the inside faces of the end members 1 and 2. The inner ends of the springs 22 are connected to the journal members 17 as indicated in Fig. 4 and the outer ends are bent around pins 23 projecting from the faces of the end plates 1 and 2.

In order to limit the rotative movement of the brush supporting rods 16, washers 24 on the threaded bushings 20 are employed and are provided with projecting portions 25 adapted to contact with the pins 26 projecting from the journal members 17 as shown in Fig. 1. This limitation on the rotative movement of the brush supporting rods 16 is necessary to prevent the brushes from being moved toward the conducting plates beyond desirable limits.

The brushes 27 are those which contact with the conducting plates 7 while the brushes 28 positioned between the brushes 27 as shown in Fig. 1 contact with the conducting discs 6. The brushes 27 and 28 may be, and preferably are, in the form of flat strips of resilient material and are mounted upon the brush supporting rods 16 by means of the clamping members 29 and 30, to which the brushes are fastened by means of screws 31. The clamping members are insulated from the brush supporting rods 16 by means of the tubes 32 of insulating material and are held in position by the bolts 33. It will be appreciated that the positions of the brushes 27 and 28 on the supporting rods 16 are adjustable. Said adjustment is necessary because it is not possible to obtain commercially insulating discs 9 and 15 of uniform thicknesses, so that the distances between the conducting plates 6 and 7 vary with the thicknesses of the insulating discs.

Instead of the brushes of flat resilient material, two or more resilient wires, having loops therein as indicated at 34 in Fig. 2, may be employed.

The brush contacts 35 mounted upon the ends of the brushes 27 and 28 and contacting with the conducting plates 7 and 6 respectively, are preferably in the form of flat strips of metal bent back upon themselves to form a U between the parallel arms of which the ends of the brushes 27 and 28 are inserted. The brush contacts 35 may be brazed or otherwise fastened to the brushes.

It will be appreciated from the above description of the means employed for supporting the brushes and the construction of the

brushes themselves and the brush contacts mounted thereon, that any wear occurring in the brush contacts will be taken up by the resiliency of the brushes themselves forcing the brush contacts toward the conducting plates, and also by means of the tendency of the brush supporting rods to rotate by virtue of the coil springs 22 associated therewith. As one side of the brush contacts 35 wears through to the brushes themselves, the brushes may be reversed so as to utilize the other side of the brush contacts.

As shown in Fig. 1, for example, the brushes 28 contact with the conducting discs 6 continuously throughout the rotation of the central shaft. As the circuit is therefore not broken between the brushes 28 and the conducting discs 6, no sparking will occur on the surface of the discs. On the other hand, the brushes 27 contact with the segmental projections 12 on the conducting plates 7 and the circuit is broken between the brushes and the plates 7 every time the switch is turned from one position to another. No sparking occurs on the surface of the plates 7 since the conducting plates 7 are bevelled as indicated at 13 in Fig. 2, and any sparking will be along these bevelled surfaces 13. This prevents the surfaces of the projecting segments 12 from being pitted or otherwise marked by sparking. As the bevelled surfaces 13 are extended below the periphery of the insulating washers 9, any sparking will occur in or along the chamber formed by the washers 9 and bevelled surfaces 13. It has been found that sparking thus which may occur in this chamber is quenched more rapidly than sparking occurring through a more open space.

As will be apparent from Fig. 1, the brushes 27 are substantially the same width as the combined thicknesses of the conducting plates 7 and the insulating washers 9 on either side thereof. When the brushes 27 are not in contact with the projecting segments 12 they rest upon the insulating washers 9. As the thickness of these washers is less than the thickness of the conducting plates 7 the friction on the brushes is reduced thus making the central shaft 4 easier to rotate.

The various circuits controlled by the switch are connected to the brushes by means of the terminal members 30' connected to the brush clamping members 30 as shown in Figs. 2 and 3.

In order to inform the operator when the central shaft with the conducting plates mounted thereon has been rotated a sufficient amount to break the circuit through one series of brushes and to connect the circuit in the next succeeding series of brushes, the position indicating means described below are employed.

A disc 36 is mounted upon the central shaft 4 at one end thereof and has cut therein six

notches indicated at 37 in Fig. 3. The rod 10 passing through the conducting plates 6 and 7 also passes through the disc 36 to prevent it from being moved with respect to the central shaft 4. A follower 38 is pivotally mounted on one of the tie rods 3 as shown in Fig. 3, so that the member 38 is in alignment with the disc 36. A small roller 39 is rotatably mounted in the follower 38 as indicated in Fig. 1 and is adapted to contact with the surface of the conducting disc 36, and to engage in the notches 37 in this disc. In order to force the roller 39 into contact with the conducting disc 36 a spring 40 is connected to the end of the follower 38 and to a pin 41 projecting from the inner surface of the end member 1 as shown in Fig. 3.

In the modification shown in Figs. 6 and 7 slightly different means for supporting the brushes are employed. The brushes 27 are fastened to supporting plates 42 by means of the screws 43. The plates 42 are substantially rectangular in form and have U-shaped recesses 44 cut in one vertical edge and U-shaped recesses 45 cut in the lower horizontal edge. The plates 42 are positioned over the brush supporting rods 46 which are threaded as shown in Fig. 7 so that the rods are located in the recesses 44 and 45. The plates are held in position on the supporting rods 46 by means of the locking nuts 47. The upper edges of the plates 42 are bent over as indicated at 48 to provide a supporting surface for the brushes 27.

It will be readily understood from the above description that the positions of the brushes 27 may be readily adjusted on the supporting rods 46 to accommodate any varying thicknesses of the insulated washers between the conducting plates on the central shaft. The means employed in this modification for rotating the supporting rods 46 so as to urge the brushes 27 toward the conducting discs comprise a projecting portion 49 on the journal members 50 which are rotatably supported in the end plates 1 and 2 and a spring 51 connected to the projections 49 and to a pin 52 projecting from the inner surface of the end plate.

Instead of using the metal brush contacts 35, previously described, carbon brush contacts 27' such as are shown in Fig. 6 may be employed. As carbon brush contacts have a longer life their use may be preferred under certain conditions of operation.

In the modification shown in Figs. 8 and 9, instead of the double brush supporting rods, a single rod, preferably of square cross-section, is employed as shown at 53. U-shaped clamping members 54 are mounted on the rods 53 and held in position thereon by means of the clamping plates 55 and the locking nuts 56. The brushes 27 are mounted upon the clamping plates 55 and held in position by the locking nuts 56. As only a single rod is em-

ployed for supporting each series of brushes no journal members are necessary but the ends of the supporting rods 53 are made circular and the rods are rotatably supported in the end plates 1 and 2. Rotation of the rods 53 to take up the wear of the brush contacts is obtained by means of a spring 57 connected to a projection 58 on the supporting rods, and to a pin 59 projecting from the inner surface 10 of the end plate 1.

The means for limiting the rotative movement of the supporting rods 46 and 53, respectively, indicated generally as 60 in Figs. 7 and 9, are similar to the means previously 15 described in connection with the preferred embodiments of the invention and need not be further described here.

As means for producing a quicker separation between the projections 12 and the 20 brushes 27, than can be accomplished by a progressive turning of the handle by hand alone, a snap action is provided by having the handle 5 connected with the central shaft 4 through the intermediary of a helical spring 25 61 (Fig. 10). A part of the hub 62 of the handle 5 is free to turn on the shaft 4 but is retained thereon by a pin 63 which enters a groove 64 in the shaft 4. The other part 64, of the hub 62 is fixed to the shaft 4. One end 30 of the spring 61 is fixed to the hub 62 and the other end thereof to the part 64. The part 64 carries a pointer 65 which will indicate to the operator in what position the switch is placed at all times. A rotative movement given to 35 the handle 5 will first produce a tension on the spring 61 until it is sufficient to cause the follower 39 to be forced out of one of the depressions 37 and when a point between the depressions is reached the follower 37 will drop automatically with a snap action into the 40 next depression owing to a release of the tension on the spring 61, thereby causing a greatly accelerated separation between the projections 12 and the brushes 27. Obviously 45 this action will practically eliminate any tendency of sparking or arcing between the contacts.

Having thus described these specific embodiments of my invention, I do not wish to 50 be understood as being limited to the details set forth, for the construction and arrangement of parts may be altered as the occasion requires, or the construction of the apparatus may be otherwise modified by 55 those skilled in the art without departing from the spirit and scope of the invention as set forth in the appended claims.

What is claimed and desired to be protected by Letters Patent is:

60 1. In a switch for controlling a plurality of circuits comprising, end members adapted to support a rotatable shaft, the improvement which comprises a plurality of conducting plates having peripheral projections and fixed 65 on said shaft, a plurality of brushes adapted

to contact with each of said plates, and means for holding said brushes out of contact with said plates.

2. In a switch for controlling a plurality of 70 circuits comprising, end members adapted to support a rotatable shaft, the improvement which comprises a plurality of conducting plates having peripheral projections and fixed on said shaft, a plurality of brushes adapted to contact with said plates, and means carried by said shaft adjacent said plates for holding said brushes out of contact with said plates.

3. In a switch for controlling a plurality of 75 circuits comprising, end members adapted to support a rotatable shaft, the improvement which comprises a plurality of conducting plates having segmental projections and fixed on said shaft, a plurality of brushes adapted to contact with each of said plates, and insulating members carried by said shaft adjacent said plates for holding said brushes out of contact with said plates.

4. In a switch for controlling a plurality of 80 circuits comprising, end members adapted to support a rotatable shaft, the improvement which comprises a plurality of conducting plates having segmental projections and fixed on said shaft, a plurality of brushes adapted to contact with said plates, a plurality of 85 brush supporting members rotatably supported by said end members, insulating disks carried on said shaft adjacent said plates for holding said brushes out of contact with the peripheries of said plates, and means connected to said supporting members and adapted to rotate the same whereby said brushes are urged into contact with said insulating disks and projections.

5. A switch for controlling a plurality of 90 circuits comprising, end members adapted to support a rotatable shaft, a plurality of circular conducting discs on said shaft, a plurality of conducting plates on said shaft having segmental projections, a plurality of 95 circular insulating discs on said shaft whose radii exceed the radii of the circular discs but are less than the radii of said segmental projections, a plurality of brush supporting members, a plurality of brushes mounted on said brush members and contacting with said conducting discs and plates, and means connected to said brush supporting members and adapted to urge said brushes into contact with said discs and plates.

6. A switch for controlling a plurality of 100 circuits comprising, end members adapted to support a rotatable shaft, a plurality of circular conducting discs on said shaft, a plurality of 105 conducting plates on said shaft having segmental projections, a plurality of circular insulating discs on said shaft whose radii exceed the radii of the circular discs but are less than the radii of said segmental projections, a plurality of brush supporting 110 members, a plurality of brushes mounted on said brush members and contacting with said conducting discs and plates, and means connected to said brush supporting members and adapted to urge said brushes into contact with said discs and plates.

7. In a switch for controlling a plurality of 115 circuits comprising, end members adapted to support a rotatable shaft, a plurality of circular conducting discs on said shaft, a plurality of 120 conducting plates on said shaft having segmental projections, a plurality of circular insulating discs on said shaft whose radii exceed the radii of the circular discs but are less than the radii of said segmental projections, a plurality of brush supporting 125 members, a plurality of brushes mounted on said brush members and contacting with said conducting discs and plates, and means connected to said brush supporting members and adapted to urge said brushes into contact with said discs and plates.

members rotatably supported by said end members, a plurality of brushes mounted on said brush members and contacting with said conducting discs and plates, and means connected to said brush supporting members and adapted to rotate the same whereby said brushes are urged into contact with said discs and plates.

10 7. A switch for controlling a plurality of circuits comprising, end members adapted to support a rotatable shaft, a plurality of circular conducting discs on said shaft, a plurality of conducting plates on said shaft having segmental projections, a plurality of circular insulating discs on said shaft whose radii exceed the radii of the circular discs but are less than the radii of said segmental projections, a plurality of brush supporting members rotatably supported by said end members, a plurality of brushes mounted on said brush members and contacting with said conducting discs and plates, means connected to said brush supporting members and adapted to rotate the same whereby said brushes are urged into contact with said discs and plates, and means adapted to limit the rotative movement of said brush supporting members.

8. A switch for controlling a plurality of circuits comprising end members adapted to support a rotatable shaft, a plurality of circular conducting discs on said shaft, a plurality of conducting plates on said shaft having segmental projections, a plurality of circular insulating discs on said shaft whose radii exceed the radii of the circular discs but are less than the radii of said segmental projections, a plurality of brush supporting members rotatably supported by said end members, a plurality of brushes mounted on said brush members and contacting with said conducting discs and plates, adjustable means for positioning said brushes on said brush supporting members, means connected to said brush supporting members and adapted to rotate the same whereby said brushes are urged into contact with said discs and plates and means adapted to limit the rotative movement of said brush supporting members.

50 9. A switch for controlling a plurality of circuits comprising, end members adapted to support a rotatable shaft, a plurality of circular conducting discs on said shaft, a plurality of conducting plates on said shaft
55 having segmental projections, a plurality of circular insulating discs on said shaft whose radii exceed the radii of the circular discs but are less than the radii of said segmental projections, a plurality of brush supporting
60 members rotatably supported by said end members, a plurality of brushes mounted on said brush members and contacting with said conducting discs and plates, adjustable means for positioning said brushes on said
65 brush supporting members, means connected

to said brush supporting members and adapted to rotate the same whereby said brushes are urged into contact with said discs and plates, means adapted to limit the rotative movement of said brush supporting members, having segmental projections, a plurality of a disc on said shaft having grooves therein and a member adapted to engage in said grooves to indicate when the circuits through said brushes are made and broken. 75

10. A switch for controlling a plurality of circuits comprising, end members adapted to support a rotatable shaft, a plurality of circular conducting discs on said shaft, a plurality of conducting plates on said shaft having segmental projections, a plurality of circular insulating discs on said shaft whose radii exceed the radii of the circular discs but are less than the radii of said segmental projections and whose thicknesses are substantially less than the thicknesses of said conducting plates, a plurality of brush supporting members, a plurality of brushes mounted on said brush members and contacting with said conducting discs, a plurality of brushes adapted to contact with said segmental projections and adapted to contact with said insulating discs when not contacting with said segmental projections whereby the resistance to rotation of said shaft is lessened, and means connected to said brush members and adapted to urge said brushes into contact with said discs and plates.

11. A switch for controlling a plurality of circuits comprising, end members adapted to support a rotatable shaft, a plurality of circular conducting discs on said shaft, a plurality of conducting plates on said shaft having segmental projections, a plurality of circular insulating discs on said shaft whose radii exceed the radii of the circular discs but are less than the radii of said segmental projections and whose thicknesses are substantially less than the thicknesses of said conducting plates, a plurality of brush supporting members, a plurality of brushes mounted on said brush members and contacting with said conducting discs, a plurality of brushes adapted to contact with said segmental projections and adapted to contact with said insulating discs when not contacting with said segmental projections whereby the resistance to rotation of said shaft is lessened, said conducting plates lying wholly within the margins of said insulating discs except for said segmental projections whereby a recess is formed which is adapted to confine sparking action occurring when the circuits through said conducting plates are broken, and means connected to said brush members and adapted to urge said brushes into contact with said discs and plates. 100 105 110 115 120 125

12. In a switch for controlling a plurality of circuits and having end members adapted to support a rotatable shaft, the combination

tion of a plurality of conducting plates carried on said shaft and insulated therefrom, a plurality of brushes adapted to contact with each of said plates in certain portions thereof, a plurality of brush supporting members, means connected to said brush supporting members and adapted to urge said brushes into contact with said plates, insulating members for holding said brushes out of contact with said plates in certain positions thereof, a handle for rotating said shaft, means for retaining said shaft in a plurality of said positions, and a spring connection between said shaft and said handle for producing a snap action between said conducting plates and said brushes.

In testimony whereof, I have affixed my signature hereto on May 28, 1929.

WILLIAM L. WALKER.
